UNITED STATES PATENT OFFICE.

FRED H. WEINHAUER, OF NEW YORK, N. Y.

SPARK-PLUG.

No. 920,702.

Specification of Letters Patent.

Patented May 4, 1909.

Application filed September 26, 1908. Serial No. 454,926.

To all whom it may concern:

Be it known that I, FRED H. WEINHAUER, a citizen of the United States, residing in the borough of Manhattan, city, county, and State of New York, have invented an Improvement in Spark-Plugs, of which the following is a specification.

My invention relates to a spark plug and to such as are employed for the electrical ignition of the explosive mixture in the cylinders of gas and oil engines, and particularly to a spark plug of the so-called jump spark type in contradistinction to that type of plug in which a break spark is employed.

Heretofore so far as I am aware the jump spark plugs have been so constructed that there is more or less of a tendency of short circuiting the high tension current employed; the short circuit being between the shell or ground electrode and the binding post or other connection to which the shell or interior electrode is electrically connected, such short circuits being commonly caused by water or moisture collecting or otherwise adhering to the outer surface and extending between the said binding post and shell, and as it will be understood, is unavoidable in many cases,—for instance in the use of marine motors in small boats when the spray is dashed over the sides.

Now the object of my invention is the provision of a spark plug in which the possibility of short circuiting the spark points is obviated and at the same time to provide in a spark plug a novel joint for electrically and mechanically connecting the plug to the cable leading thereto from the coil box.

In carrying out my invention, I employ the usual shell or body adapted to be connected to the cylinder head of the gas, oil or other explosive engine. This shell as is customary comprising a ground terminal of the plug, a shell terminal, an insulating collar for the shell terminal, means whereby the shell terminal is secured in the insulating collar, means for securing the said shell terminal and its insulating collar within the said shell and means for connecting a cable both mechanically and electrically to the said shell electrode and within the said shell, as will be hereinafter more particularly described.

In the drawing, Figure 1 is a central longitudinal section illustrating my improved spark plug. Fig. 2 is a section on line x , x , Fig. 1. Fig. 3 is a section of the outer end of the plug showing the parts before they are

clamped into position as shown in Fig. 1. Fig. 4 is a central longitudinal section of the clamping sleeve employed within the shell of the plug and Fig. 5 is an elevation and partial section of the end of the cable and the nipple therefor employed thereon in making the connection at the coil box.

Referring particularly to the drawing, 10 designates the shell or body of the spark plug 65 and is preferably made of suitable metal of good conductivity and provided at one end with a screw-threaded shank 11 adapted to be received in a suitable opening in the cylinder head of a gas, oil, or other explosive 70 engine. The screw-threaded end 11 is provided with a bore indicated at 12 terminating at a shoulder 14 from which extending partially through the shell 10 is a bore 13 of larger diameter than the bore 12; the 75 bore 13 being terminated by a shoulder 13¹ from which to the outer end of the shell extends a bore 15 which is screw threaded and of larger diameter than the bore 13.

16 designates the shell electrode the section of which for the greater part of its length is hexagonal as shown in Fig. 2, or as will be understood, may be of any other flat sided configuration. One end of the shell electrode 16 is provided with a spark pin 17 80 and the opposite end of the shell electrode is screw-threaded and so adapted to receive a nut 18.

19 designates a barrel of insulating material having approximately centrally of its 90 length a peripheral flange 21 of such a diameter as to fit snugly within the bore 13; the diameter of the other portions of the said barrel being slightly smaller than the bore 12 so that the lower end of the barrel fits 95 within this bore 12.

Between the shoulder 14 and that formed by the peripheral flange 21 on the insulating barrel, I employ the insulating packing material indicated at 22 and on the opposite 100 side of the peripheral flange 21 I also employ a ring of insulating packing material indicated at 23. The shell electrode 16 as is customary passes entirely through the insulating barrel 19, and between the shoulder 105 formed between the hexagonal portion of the shell electrode and the enlarged end thereof and the corresponding shoulder formed in the bore provided in the insulating barrel for the shell electrode, I employ a 110 ring of insulating packing material indicated at 20 and the said shoulder and shell elec-

trode are drawn tight against the said ring of insulating material 20 by drawing up the nut 18 against the inner end of the insulating barrel 19. Now over the inner end of the insulating barrel 19 I employ a gland indicated at 24 which may be made of any suitable material and is adapted to bear against a ring 23 of insulating material and to force the same down against the peripheral flange 21 of the barrel 19 and in turn to force the ring 22 against the shoulder 14 to make a tight joint between these parts to prevent the escape of the combustible gases from the engine cylinder.

15 Within the bore 15 at the outer end of the shell I employ a thimble indicated at 25 which is exteriorly screw-threaded and adapted to be turned down against the gland 24 to effect the joint aforesaid.

20 26 indicates a cylindrical block preferably made of insulating material and provided at one end with a recess which as indicated is semi-circular and adapted to receive the semi-circular nut 18 and to rest against and 25 overlap the inner end of the barrel 19 and to surround the said nut 18. This block 26 is also provided with a small longitudinal centrally disposed bore, the purpose of which is hereinafter stated.

30 27 represents a sleeve adapted to fit within the bore 15 of the shell and at one end to fit over the block 26, being provided with a bore of one diameter for this purpose and a bore of larger diameter to receive a cable, 35 the cover of which is indicated at 28, while 29 designates a sheath of insulating material and 30 the wire or conductor member of the cable; the said wire 30 being passed through the bore aforesaid in the block 26 and into a 40 recess provided therefor in the inner end of the shell electrode 16; the cover and the insulating sheathing of the cable being removed from the end thereof and adapted to abut against the inner end of the insulating 45 block 26, all of which is plainly indicated in Fig. 1 of the drawing.

31 designates a bushing which is exteriorly screw-threaded and adapted to be received within the screw-threaded bore 15 of the 50 shell 10. It will be noted that the inner extremity of the sleeve 27 is tapered as indicated at *a* and that the inner end of the bushing 31 is interiorly tapered as indicated at *b* and at a different angle to the taper effected 55 on the end of the sleeve 27; the bushing 31 being preferably made integral with the flat-sided head 32 by means of which the same is screwed down against the ends of the sleeve 27 from the position shown in Fig. 3 to that 60 indicated in Fig. 1, whereby the tapered end of the sleeve 27 is forced into the cover and sheathing of the cable to such an extent that a tight mechanical joint is effected securely holding the cable in position within the plug 65 and at the same time the tendency of the

bushing 31 in gripping the sleeve 27 and forcing the same into the cable sheathing is to move the cable slightly farther into the shell, thereby causing the end of the cable conductor wire 30 to seat positively against 70 the base of the recess in the inner end of the shell electrode 16 to insure a good electrical connection between these parts. At the opposite end of the cable or that to which the connection is made to the coil box, I prefer to employ a nipple indicated at 33 which is preferably provided with an elongated end through which a bared portion of the conductor wire 30 of the cable is passed and thereby adapted to be secured to the binding 80 post or other suitable connection on the coil box; the end of the cover and insulated sheathing of the cable passing a material distance into the said nipple; it being apparent that any possible short circuiting between 85 the connection at the coil box and the shell of the cable or ground electrode by moisture collecting on the cable will be overcome by the break in such a short circuit made by the nipple 33.

90 It will also be understood that I prefer to make the insulating barrel 19 of porcelain, the block 26 and sleeve 27 of compressed fiber, or that other materials of equally good insulating qualities may be employed in 95 their stead.

I claim as my invention:

1. A spark plug comprising a shell, a shell electrode, an insulating barrel for said shell electrode, means within said shell for maintaining the said shell electrode and barrel in position therein, a cable sleeve within the said shell abutting against the said means, a cable, and an end member adapted to interiorly engage the said shell and to force the end of the said cable sleeve into the sheathing of said cable to secure the cable which passes through said end member and cable sleeve to the shell electrode and to insure the electrical connection between the cable and the said shell electrode.

100 2. A spark plug comprising a shell, a shell electrode, an insulating barrel for said shell electrode, means adapted to be screwed down within the said shell to secure the said shell electrode and its barrel in position 105 therein, an insulating cable sleeve fitting freely within the said shell and adapted to abut against the aforesaid means, a cable, and an end member adapted to interiorly engage 110 the said shell and to force the end of the said cable sleeve into the sheathing of said cable which passes through the said end member and cable sleeve so as to secure the cable to the spark plug, and also to insure the electrical 115 connection between the cable and the shell electrode.

120 3. A spark plug comprising a shell, the body portion of which is interiorly screw threaded, a shell electrode, an insulating bar- 130

rel for said shell electrode, a thimble exteriorly screw threaded and adapted to be screwed down within the said shell to maintain the said shell electrode and its insulating barrel in position within the said shell, a cable, a cable sleeve of insulating material abutting against the end of the said thimble, a bushing adapted to be screwed down within the said shell and to engage and force the 10 end of the said cable sleeve into the sheathing of said cable which passes through the said bushing and cable sleeve to secure the cable to the plug and to insure the electrical connection between the cable and the shell 15 electrode.

4. A spark plug comprising a shell, the body portion of which is interiorly screw threaded, a shell electrode having a recess in its inner extremity, an insulating barrel for 20 the shell electrode, means for maintaining the shell electrode within the insulating barrel, a thimble exteriorly screw threaded and adapted to be screwed down within the said shell to maintain the said shell electrode and 25 its insulating barrel in position within the said shell, a cable, a cable sleeve of insulating material abutting against the end of the said thimble, a bushing adapted to be screwed down within the said shell and to engage and force the end of the said cable sleeve into the sheathing of said cable which passes through the said bushing and cable sleeve to secure the cable to the plug and to 30 seat the cable in the said recess in the end of 35 the shell electrode and so insure the electrical connection between the said parts.

5. A spark plug comprising a shell, a shell electrode, an insulating barrel, means for securing the shell electrode within the insulating barrel, a thimble fitting within the said shell and adapted to secure the said shell electrode and insulating barrel within the shell, a block adapted to pass within the said thimble to bear against the inner end of the 40 said insulating barrel, and means for mechanically and electrically connecting a 45

cable within said shell and to the said shell electrode.

6. A spark plug comprising a shell, a shell electrode, an insulating barrel, means for securing the shell electrode within the insulating barrel, a thimble fitting within the said shell and adapted to secure the said shell electrode and insulating barrel within the shell, a block adapted to pass within the 50 said thimble to bear against the inner end of the said insulating barrel, a cable, a sleeve fitting within said shell and adapted to pass over the said block and bear against and overlap the end of the said thimble and also 55 to receive said cable, and means co-acting with the said sleeve to form a tight joint between the same and the cable within the said shell and to insure the electrical connection 60 between the said shell electrode and cable. 65

7. A spark plug comprising a shell, a shell electrode, an insulating barrel, means for securing the shell electrode within the insulating barrel, a thimble fitting within the said shell and adapted to secure the said shell 70 electrode and insulating barrel within the shell, a block adapted to pass within the said thimble to bear against the inner end of the said insulating barrel, a cable, a sleeve fitting within said shell and adapted to pass over 75 the said block and bear against and overlap the end of the said thimble and also to receive said cable, the exterior of said sleeve being tapered externally, and a bushing adapted to fit within the said shell and having an internally tapered extremity adapted to engage and force the said tapered end of the sleeve into the cable which passes through the said bushing and into the said sleeve to make a tight joint between the said 80 cable and sleeve and bushing. 85

Signed by me this 5th day of September, 1908.
